UNITED STATES PATENT OFFICE.

EDWIN NORTON, OF CHICAGO, ILLINOIS.

SOLDERING CANS.

SPECIFICATION forming part of Letters Patent No. 274,362, dated March 20, 1883.

Application filed October 28, 1882. (No model.)

To all whom it may concern:

Be it known that I, EDWIN NORTON, a citizen of the United States, residing in Chicago, in the county of Cook and State of Illinois, 5 have invented a new and useful Improvement in Soldering Cans, of which the following is a specification.

My invention relates to improvements in machines or apparatus for soldering cans, where- 10 in the cans are rolled on a suitable track through a bath of molten solder, and more particularly to improvements upon the process and apparatus heretofore patented to me in Letters Patent of the United States No. 233,688, 15 dated October 26, 1880.

My present invention consists in an apparatus having a track provided with an acid or flux bath and a bath of molten solder, and a chain or other suitable device for rolling the 20 cans on said track through said baths. The cans are heated by rolling them with their ends against a heated plate on the track, and the acid-bath is preferably heated also. The cans, as they pass through from the solder-bath, are 25 delivered upon an endless belt, apron, or carrier upon their ends, so that the solder will remain evenly distributed around their joints at the ends; and the recently-soldered seam is subjected to a blast of cold air, so as to more 30 quickly set the solder, as the cans pass along on the carrier. The cans are rolled over the heated plate and through the acid and solder baths by means of an endless chain mounted on adjustable pulleys. The pressure of the 35 chain upon the cans is regulated by a number of pivoted weights resting thereon, so as to insure an even rolling of the cans through the solder-bath and prevent their slipping. I also provide a rail or guard above the cans for holding them down and preventing the row of cans 40 pressing against each other, causing some of them to rise or bulge up. This rail is secured to the brackets on which the adjustable pulleys are mounted, so that the rail may likewise 45 be adjusted to cans of different diameters. The ends of the can are also held or guided against the plate by a guard or rail at their upper or outer end, which is also adjustably secured to the frame of the machine, so as to 50 accommodate cans of different lengths. The acid bath is preferably located between the

heating-plate and the solder-bath, so that the end of the can or the seam will be heated before rolling through the acid-bath. As the cans frequently roll through the machine in 55 close juxtaposition, the friction of one can against another will tend to cause some of the cans to slip or slide through the bath, and thus solder only a portion of the seam, and to effectually prevent this, in addition to the piv- 60 oted weights with which I load the chain at points, I provide at each end of the solder-bath a spring-tension pulley or tightener. The acid is supplied to the acid bath or receptacle as it is used from a reservoir above through a 65 pipe provided with stop-cocks, and the acid bath or receptacle itself, through which the can rolls, is provided with an overflow, so that the acid is always maintained at the same height. From the overflow the acid drops into a tank 70 below, and a pump is provided of suitable size for pumping the acid into the upper reservoir from time to time, so that the acid may be used over and over again.

In the accompanying drawings, which form 75 a part of this specification, and in which similar letters of reference indicate like parts, Figure 1 is a side elevation of my improved apparatus. Figs. 2, 3, and 4 are cross-sections on lines 2 2, 3 3, 4 4, respectively, of Fig. 1; and 80 Fig. 5 is a plan view.

In the drawings, A represents the framework of the machine, which is all preferably made of iron.

B is an inclined angle plate, table, or track 85 for the cans to roll upon, one on each side of the machine.

C is the heating-plate, which is secured to or forms part of the angle-piece b of the inclined table B, and against which the end of 90 the can rests as it is rolled along, and is thereby heated.

D is the conveyer-chain for rolling the can through the machine on the table B. This chain is mounted upon and driven by pulleys 95 E. The brackets E', upon which the pulleys are mounted, are adjustably secured to the frame of the machine, their heights being regulated by the adjusting-screws e.

F is the upper tank or reservoir, from which 100 the acid is supplied to the acid bath, receptacle, or depression f in the track or table B,

through a pipe, f' , which is provided with a stop-cock, f'' , by which the flow of acid may be regulated. The acid bath or receptacle f , through which the cans roll, is provided with an overflow-opening, f^3 , whereby the acid in the bath may be maintained at the height desired. The surplus acid falls through the overflow into a tank, F' , below.

F^2 is a small pump for conveying the acid again into the upper reservoir, F , so that it may be used over again.

F^3 is a heating-pipe, located beneath the acid-tank, whereby the acid is kept warm or hot, which very much facilitates the action of the acid upon the joint in preparing it for the solder. This heating pipe or device F^3 may preferably be a gas-tube provided with a number of suitable openings or jets for the gas.

G is the tank for holding the molten solder. G The track or plate B , which forms the cover of this tank, is cut out at its lower edge, forming an opening or slot, g , through which the seam or corner of the can comes in contact with the solder. The solder is heated and melted by gas-tubes g' , provided with suitable perforations.

K is an adjustable guide or rail, located above the cans and preferably secured to the adjustable brackets E' , upon which the pulleys E are mounted, so that the act of adjusting the height of the pulleys for cans of different diameters will at the same time adjust the guide K . This rail or guide serves to hold or press the cans into the solder-bath and to prevent the cans crowding together and some of them jumping or bulging upward. K' is a similar adjustable guide or rail at the outer end of the cans, secured by means of slotted braces k and adjusting-screws k' to the inclined table or track B . This guide k' , which is adjustable to cans of different lengths, serves to keep the ends of the cans against the angle-piece b of the inclined plate or table B and insures their rolling properly through the acid and solder baths and against the heating-plate.

L and L' are tension-pulleys located near each end of the solder-bath, and provided with springs l l' , whereby they are pressed against the conveyer-chain, so as to increase the pressure of the chain against the cans and cause them to roll smoothly and steadily through the solder-bath.

The end of the track or table B is preferably somewhat inclined, as shown at B' , so that the cans, after passing from under the conveyer-chain, will readily roll into the discharge opening or tube M , whereby the cans are turned upon end and delivered to the belt or carrier N . The construction of this tube N for turning the cans upon end and delivering them to a carrier is fully set forth in my Letters Patent No. 232,409, of September 21, 1880, and I do not, therefore, deem it necessary to here describe the same particularly. However, any other suitable device for turning or delivering the cans upon end to the belt or carrier may be used, provided it does not jar the can too

much, so as to disturb or injure the seam before the solder becomes hard.

O is a cold-air pipe, located above or near the belt-carrier N and provided with suitable openings or jet-tubes, o , whereby the cans, as they are carried along on the belt or carrier, are subjected to blasts or jets of cold air for the purpose of cooling the cans and setting the solder. Air is forced into the pipe by any suitable pump or apparatus.

P P are the pulleys for the belt or carrier N .

Q represents an inclined chute, by which the cans are delivered to the machine, and Q' is the discharge-chute.

R R are weights pivoted to the adjustable rail or guide K , and resting upon the conveyer-chain and located specially over the solder-bath, so as to increase the friction or pressure of the chain upon the cans for the purpose of preventing the cans sliding if they become crowded as they roll along on the track B .

The heating-plate C is heated by jets of gas from the tube S . The gas-tubes S , g' , and F^3 may be one continuous tube extending through the whole machine, and in practice I blow into the gas tube or tubes a blast of air which mixes with the gas in burning. Other means besides gas may be used for heating the apparatus. The can, as it rolls into the machine, is first heated by contact with the heating-plate, and it next rolls through the acid-bath, and then directly through the solder-bath, and is next delivered onto the carrier in a vertical position, and cooled by blasts of air as it passes along on the carrier. Both sides of the machine are alike, one side being used to solder one end of the can, and the other side the other end. The acid in the acid-bath being heated, it has no tendency to cool the seam before reaching the solder-bath. The heating-plate may, however, be located between the acid and solder baths; but the means shown is the preferable method of practicing my invention.

The pulleys on which the cooling-belt N is carried are adjusted vertically in relation to delivering device M by means of the screws n , so that cans of different lengths may bear the same relation to the delivering device and the carrier.

The spring-tension pulleys L L' are located directly over the incline or depression in the track B at each end of the solder-bath, so that the depression of the track at this place will not cause the cans to leave the chain.

I claim—

1. The soldering apparatus consisting of a track having a heating plate or device, an acid bath or receptacle, and a solder bath or receptacle, in combination with a device for rolling the cans along said track, and a belt or carrier for supporting the cans in a vertical position while being cooled, substantially as specified.

2. The combination of a track provided with heating plate or device, an acid or flux bath, and a solder-bath, with a device for rolling the cans along said track, a cooling belt or carrier,

and a device for delivering the cans from said track to said belt or carrier in a vertical position, substantially as specified.

3. The combination of a track with a heating device, an acid bath or receptacle, a solder bath or receptacle, and a chain or device for rolling the cans along said track through said baths, substantially as specified.

4. The combination, with a track provided with a heating device, an acid-bath, and a solder-bath, of a chute for delivering the cans thereto, and a device for rolling the cans along said track, substantially as specified.

5. In a soldering-machine, the combination of the inclined track or table provided with acid and solder baths and heating-plate, with a chain, for rolling the cans, mounted upon adjustable pulleys, and adjustable rails or guides above and at the end of the cans, substantially as specified.

6. The combination of the inclined track and solder-bath with the endless-chain conveyer loaded with pivoted weights to prevent the cans sliding, substantially as specified.

7. The combination of the track with the solder-bath, conveyer-chain, upper guide or rail, weights pivoted thereto, and tension-pulleys, substantially as specified.

8. The combination of the track, solder-bath, conveyer-chain, and spring-tension pulleys located near each end of the solder-bath, substantially as specified.

9. The combination, with a track having an acid bath or receptacle provided with an overflow, of an upper and lower acid-tank, substantially as specified.

EDWIN NORTON.
